UNITED STATES PATENT OFFICE.

JOHN M. BRINKLEY, OF CHICAGO, ILLINOIS.

MIXING APPARATUS.

Application filed May 29, 1926. Serial No. 112,593.

My invention relates to a mixing apparatus, the main object being to provide a simple, inexpensive and efficient mixing apparatus capable of being associated with kegs, 5 barrels, casks and similar liquid holding vessels for mixing paints and other materials and ingredients. One of the objects of my invention is to provide a mixing apparatus having support in the form of a lid or cover 10 furnished with means whereby to be fitted to different sizes of kegs, barrels and other vessels.

Another object is to provide an apparatus of this character which is so constructed and 15 arranged that it may be operated either by motor or by hand; and a further object is to provide an apparatus which is capable of employing agitator devices of different sizes.

Other objects will appear hereinafter. 20 The invention consists in the combinations and arrangements of parts hereinafter described and claimed.

The invention will be best understood by reference to the accompanying drawings 25 forming a part of this specification, and in which,

Fig. 1 represents a vertical sectional view through my improved mixing apparatus in association with a vessel containing material 30 to be mixed;

Fig. 2 represents a top plan view of the parts shown in Fig. 1;

Fig. 3 is a horizontal section taken approximately on the line 3—3 of Fig. 1; and 35 Fig. 4 is a vertical section taken approximately on the line 4—4 of Fig. 1.

The preferred form of construction as illustrated in the accompanying drawings, 40 comprises a lid 5 having a downwardly offset central region 6 to provide a bearing 7 for an upright shaft 8 which extends both above and below the lid and is rotatably seated upon the offset portion 6 and 45 surrounding the shaft as shown, there being a shoulder 10 provided on the shaft for supporting it upon the antifriction device.

Mounted upon the lid is a housing 11 through the top part 12 of which the shaft 50 8 protrudes for the application of a hand operated crank 13. Also mounted upon the lid is an electric motor 14 whose driving shaft 15 extends into the housing where it is provided with a driving pinion 16. In mesh 55 with the pinion 16 is a bevel gear 17 which is loosely mounted on the shaft 8, there be-

ing, in the present embodiment, a shoulder 18 provided on the shaft 8 for the operative support of said gear 17. Also loosely mounted upon the shaft 8 is a pinion 19 60 which is fast with the gear 17 to turn therewith; and said pinion 19 is engaged with a gear 20 loosely mounted on a stud shaft 21 fixed in the housing 11 as shown, so that said gear 20 is operatively supported upon an 65 arm 22 of the housing. Fixed to the gear 20 and loosely turning on the stud shaft 21 is a pinion 23 which is engaged with a gear 24 fixed on the shaft 8. This gearing arrangement comprises reduction gearing for 70 rotating the shaft 8 from the electrical motor 14 at reduced speed; and it will be observed in this connection that the shaft 8 may be rotated either by the electrical motor 14 or by the hand operated crank 13. 75

According to an important feature of my present invention, the lid 5 is provided with means whereby to be secured as a cover upon vessels of different transverse dimensions. In carrying out this feature of my invention, the lid 5 is provided with a plurality of slots 25 which extend radially inwardly into its body from its periphery 26. In the underface of the lid and more particularly in the walls defining the slots 25, grooves 27 80 are provided to constitute guideways for the clamping members 28 carried by screw bolts 29 arranged in the slots 25 and provided with nuts 30 whereby to secure the clamping members in the adjusted positions desired. 85 Each clamping member 28 is formed with a pair of depending arms 31 adapted to straddle the top edge of the vessel to which the lid is to be applied. The arms 31 carry screw bolts 32 adapted to be engaged with the outer and inner faces of the marginal edge of the vessel as shown, the said screw bolts being provided with heads 33 made in the form of wing-nuts whereby readily to be turned. In Fig. 1, I have shown the lid 100 clamped upon a liquid holding vessel 34; and from what has been said, taken in connection with this drawing, it will be evident that, due to the provision of the radially adjustable clamping means, the lid may be 105 secured upon liquid containing vessels of different transverse dimensions.

The preferred form of mixing device comprises a head bar 35 from which depends two mixing frames 36 and 37 each consisting of a pair of opposed side blades 38 which are connected at their bottom ends by 110

a horizontal blade 39, it being observed that the mixing frame 37 is of less size than the frame 36 and is located inwardly thereof. The head bar 35 is mounted upon the shaft 8 for ready adjustment thereon, either toward or from the lid 5; the means for adjustably mounting the head bar on the shaft consisting in providing the head bar with a transverse aperture 40 for receiving the shaft and also in providing the head bar with a thumb screw 41 for securing the head bar in the adjusted position desired. Preferably and as shown, the side blades 38 of the mixing frames are of diamond shape in cross section; while the bottom connecting blades 39 are of triangular shape in cross section, it being observed that the bottom blades 39 are arranged so that their apexes constitute cutting edges 42 and so that their top upwardly inclined surfaces 43 serve, during the rotation of the mixer, to impel the material in an upward direction. The side blades 38 of each frame preferably diverge from each other as they recede downwardly from the head bar 35. The bottom blades 39 of the frames 37 and 38 are preferably connected midway their lengths by a vertical blade 44 which is also of diamond shape in cross section. It is contemplated that different sizes of mixing devices may be interchangeably employed in connection with the shaft 8 so that the apparatus can be effectively used with vessels of different sizes.

While I have illustrated and described the preferred form of construction for carrying my invention into effect, this is capable of variation and modification without departing from the spirit of the invention. I, therefore, do not wish to be limited to the precise details of the construction set forth,

but desire to avail myself of such variations and modifications as come within the scope of the appended claims.

Having described my invention what I claim as new and desire to secure by Letters Patent is:

1. A mixing apparatus including, in combination, a lid with a projecting rotatable shaft and means for rotating the shaft; a head bar slidably and vertically adjustable on the shaft in relation to said shaft; and a mixing frame carried by said head bar and comprising a pair of diamond shaped side blades and a triangular bottom blade connecting the side blades, substantially as described. 50

2. A mixing apparatus including, in combination, a lid with a projecting rotatable shaft and means for rotating the shaft; a head bar slidably and vertically adjustable on the shaft in relation to said shaft; two mixing frames carried by said head bar and each comprising a pair of diamond shaped side blades connected by a triangular bottom blade; and a blade connection between the bottom blades of the two frames, substantially as described. 60

3. A mixing apparatus including, in combination, a lid with a projecting rotatable shaft and means for rotating said shaft; a head bar slidably and vertically adjustable on the shaft in relation to said shaft; two mixing frames carried by said head bar and each comprising a pair of diamond shaped side blades connected by a triangular bottom blade; one of said frames being of less size than the other and located inwardly thereof, substantially as described. 70

In testimony whereof I have signed my name to this specification.

JOHN M. BRINKLEY.
